UNITED STATES PATENT OFFICE.

CHARLES B. HALL, OF CHICAGO, ILLINOIS.

BOTTLE-CARRIER.

No. 845,947.

Specification of Letters Patent.

Patented March 5, 1907.

Application filed October 31, 1904. Serial No. 230,670.

To all whom it may concern:

Be it known that I, CHARLES B. HALL, a citizen of the United States, residing at Chicago, in the county of Cook and State of Illinois, have invented certain new and useful Improvements in Bottle-Carriers, of which the following is a specification, reference being had therein to the accompanying drawing.

10 This invention relates to improvements in bottle-carriers, and consists of the organization and arrangement of parts hereinafter described, and particularly pointed out in the appended claims.

15 In the accompanying drawings, Figure 1 is a side elevation of a bottle-carrier made in accordance with my invention. Fig. 2 is a plan view of the same. Fig. 3 is an end elevation showing the manner of fastening or 20 securing the top and bottom border-wires. Fig. 4 is a section on the line 4-4 of Fig. 2, and Fig. 5 is a section on the line 5-5 of Fig. 4.

As clearly shown in the drawings, the sides and ends of the carrier are made of wire or wire 25 mesh 10, consisting of diagonally-disposed crossing wires. The wire mesh forming the sides and ends of the carrier are connected to top and bottom border-wires 11 and 12. The connection between the wires of the side 30 and ends with the border-wires 11 and 12 may be of any suitable character, as by bending the wires forming the sides and ends around or partially around the wires 11 and 12, as indicated by 13.

35 The carrier may be of any suitable shape, and in the present instance I have shown the same as rectangular in outline, although it is to be understood that this is immaterial and that I do not restrict myself in this particu-

40 lar, as any other suitable shape may be employed. The sides and ends may be of any suitable height and of any suitable size mesh. The top and bottom border-wires 11 and 12 are spaced apart by the wires forming sides

45 and ends of the carrier and are secured together by such side and end wires. The ends of the border-wires 11 and 12 may be secured in any suitable manner, as by bending the ends 14 of the wire 11 at a right angle and

50 extending them toward the similar angular ends 15 of the other border-wire 12, as shown in Fig. 3. As thus arranged the ends 14 and 15 are brought close together in parallel arrangement and connected or secured by 55 clips 16. This arrangement provides a se-

cure fastening for the ends of the border-wires and adds to the strength of the carrier.

Located within the sides and ends of the carrier is a bottle-support 17. This support is carried at a suitable distance from the bottom of the carrier and consists of series of wires 18 and 19. Each series of wires 18 and 19 is disposed diagonally, the wires 18 being transverse the wires 19, as clearly shown in Fig. 5, and have their ends attached to a border-wire 20 of the same outline as the border-wires 11 and 12. The wire 20 is secured to the sides and ends of the carrier in any suitable manner, as by means of wire clips 21. By reason of this transverse disposition and equidistant spacing of the wires 18 and 19 square openings are provided, which serve as pockets to receive the necks of the bottles, the wires serving as supports upon which the shoulders at the necks of the bottles rest.

In addition to the support 17 I preferably employ a series of longitudinal wires 22 and crossing wires 23, located above the wires 18 and 19. The ends of the wires 22 and 23 are 80 connected or attached to a border-wire 24, located between the border-wires 20 and the top border-wire 11. The wires of each series 22 and 23 are equidistantly spaced and provide square openings, each of which is located directly over and registers with an opening in the support 17. When a bottle is in position in the carrier, as shown in dotted lines in Figs. 2 and 4, the shoulder at the neck of the bottle rests on the wires 18 and 90 19, while the wires 22 and 23, being engaged by the sides of the bottle, prevent the latter from tilting and at the same time space the bottle from adjacent bottles.

The border-wires 11, 12, 20, and 24 are 95 made of heavier wire than the wires 18 and 19 and the wires 22 and 23 and provide a strong and rigid frame for the structure.

A web 25 is located at each corner of the carrier, preferably in the angle formed by the 100 bends in the bottom wire 12, and such webs may be made of wire, as shown. The object of these webs 25 is to prevent the telescoping of one carrier upon another when a number of carriers are piled up on top of each other. 105 It is obvious that if one carrier be placed upon another, so that the corner of an upper carrier overhangs the corner of the one under the same, the web 25 at such corner will prevent the upper carrier from tilting or slipping 110.

down and serve to sustain the weight of the same. These webs 25 may be made of any wire suitable to properly carry the weight of a carrier when filled with bottles and preferably have the wires forming the same attached to the wire 12, although they may of course be located at the top corners.

The construction and arrangement described provides a light bottle carrier or 10 crate which is exceedingly strong, durable, and rigid. By reason of the diagonal arrangement of the wires 18 and 19 and the longitudinal and transverse arrangement of the wires 22 and 23 the sides of the bottle- 15 carrier are securely braced in all directions, so that it is practicably impossible to crush the carrier by a force or pressure applied at the corners or sides, and by making the bottle-carrier of wire the latter is of relatively 20 light weight. In order to increase the resistance or strength of the carrier, the wires 18, 19, 22, and 23 are preferably corrugated.

Having described my invention, what I claim, and desire to secure by Letters Patent 25 of the United States, is—

1. A bottle-carrier having wires forming its sides and ends, top and bottom border-wires to which the side and end wires are attached, upper and lower intermediate bor-

der-wires attached to the sides and ends, longitudinal and transverse wires attached to the upper intermediate border-wire to form partitions for the bodies of the bottles, and a bottle-support consisting of diagonally-arranged crossing wires attached to the lower 30 intermediate border-wire and providing openings for the bottle-necks smaller than and in register with the openings formed by the partitions for the bodies of the bottles.

2. A bottle-carrier having wire sides and 35 ends, top and bottom border-wires attached to the sides and ends, upper and lower intermediate border-wires attached to the sides and ends, a bottle-support consisting of crossing wires attached to the lower intermediate border-wire and providing openings for the bottle-necks, crossing wires attached to the upper intermediate border-wire and providing relatively larger openings than 40 and registering with the support-openings, 45 and corner-webs attached to the carrier.

In testimony whereof I affix my signature in presence of two witnesses.

CHARLES B. HALL.
